UNITED STATES PATENT OFFICE

WILLIAM C. BURROUGHS, OF GUILFORD, CONNECTICUT

DESIGN FOR A LAMP

Application filed August 8, 1929. Serial No. 32,330. Term of patent 3½ years.

To all whom it may concern:

Be it known that I, WILLIAM C. BURROUGHS, residing at Guilford, in the county of New Haven and State of Connecticut, a citizen of the United States, have invented a new, original, and ornamental Design for a Lamp, of which the following is a specification, reference being had to the accompanying drawing, forming part thereof.

The figure is a perspective view of the lamp showing my new design.

I claim:

The ornamental design for a lamp, as shown.

WILLIAM C. BURROUGHS.
